(57) **CLAIM**

The ornamental design for a handle for cookware, as shown and described.

DESCRIPTION

FIG. 1 is a front perspective view of a handle for cookware, showing my new design;

FIG. 2 is an exploded front perspective view thereof;

FIG. 3 is an exploded rear perspective view thereof;

FIG. 4 is an exploded top plan view thereof;

FIG. 5 is an exploded bottom plan view thereof;

FIG. 6 is an exploded right-side elevational view thereof, the exploded left-side elevational view being a mirror image thereof;

FIG. 7 is an exploded rear elevational view thereof;

FIG. 8 is an exploded front elevational view thereof, illustrated with a cookware portion omitted for clarity of illustration; and,

FIG. 9 is a cross-sectional view thereof, taken along line 9-9 of FIG. 4.

The broken lines showing cookware and a screw depict environmental matter and form no part of the claimed design. The dot-dash broken lines represents a boundary of the claimed design. The remaining broken lines show portions of the handle for cookware that form no part of the claimed design.

1 Claim, 8 Drawing Sheets
